UNITED STATES PATENT OFFICE.

CATHERINE M. HANNON, OF STATEN ISLAND, NEW YORK.

DESIGN FOR A RUBBER BATHING GARTER.

Application filed October 15, 1925. Serial No. 15,124. Term of patent 7 years.

To all whom it may concern:

Be it known that I, CATHERINE M. HANNON, a citizen of the United States, residing at Staten Island, county of Richmond, city and State of New York, have invented a new, original, and ornamental Design for Rubber Bathing Garter, of which the following is a specification, reference being had to the accompanying drawing, forming part hereof.

The figure is a perspective view of a rubber bathing garter, showing my new design.

I claim:

The ornamental design for a rubber bathing garter as shown.

CATHERINE M. HANNON.
